UNITED STATES PATENT OFFICE

GEORGE E. DARROW, OF EUGENE, OREGON.

PROCESS OF REMOVING STAINS FROM FABRICS.

1,164,705.

Specification of Letters Patent. Patented Dec. 21, 1915.

No Drawing.

Application filed April 11, 1914. Serial No. 831,251.

To all whom it may concern:

Be it known that I, GEORGE E. DARROW, citizen of the United States, residing at 774 Willamette street, Eugene, in the county of 5 Lane and State of Oregon, have invented certain new and useful Improvements in Processes of Removing Stains from Fabrics, of which the following is a specification.

This invention relates to new and useful 10 cleaning compounds for use particularly in processes for removing stains of all kinds from fabrics, more especially white goods of vegetable fabric, such as cotton, linen, straw and paper and the primary object is 15 to provide solutions which when applied, will not injure the fabric and which will render the process more expeditious and cheaper.

In carrying out the process, I use two 20 separate and distinct solutions which for convenience will be termed solution A and solution B. Solution A consists of three parts of a saturated solution of oxalic acid and one part of full strength sulfurous acid. 25 Solution B consists of calcium hypochlorite, or calcium oxychlorid, with aromatics and perfume, combined in desirable proportions.

In the process of removing a stain from the fabric, a predetermined amount of the 30 solution A is first applied thereto whereupon a similar or any predetermined amount of solution B is applied. It may be here remarked that the complete compound comprises reaction product of three essential ingredients, any one of which, if merely applied 35 to a stain or coloring matter, would be

ineffective, although if permitted to remain for some length of time would destroy the color and in most instances also destroy the goods. However, by first applying solution 40 A to the stain and then applying solution B thereto a product is formed, the same being a gaseous combination of chlorin and oxygen. This gas instantly disintegrates the coloring matter, leaving the goods white and 45 absolutely free from injury.

I am aware that the three main ingredients of my compound have been used individually heretofore for cleaning purposes, but my invention consists in the particular 50 combination of the three main compounds which generate a new and active stain-removing product.

It has been stated above that this compound is particularly adapted for use on 55 vegetable fabrics but the same may also be used as well for the removal of stains from certain classes of wool and silk. In such uses, however, the solutions must be applied with considerable judgment. 60

What I claim is:

The process of removing stains from fabrics consisting in subjecting the stained fabric to a solution of oxalic and sulfurous acids and then applying a solution of calcium 65 hypochlorite thereto.

In testimony whereof I affix my signature in presence of two witnesses.

GEORGE E. DARROW.

Witnesses:

W.M. G. MARTIN,
